ABSTRACT

A wood truss, or lattice girder, arrangement with finger scarfing of only alternate generally parallel members to the chords, with oppositely inclined generally parallel web members only to the inclined webs. Material reduction of web to chord to web transference achieved producing a stronger truss with webs of the same size.

2 Claims, 4 Drawing Figures

WOOD TRUSS ARRANGEMENT

This application is a continuation of application Ser. No. 830,450, filed Jan. 4, 1969, and now abandoned.

FIELD OF THE INVENTION

The invention relates to wood trusses having upper and lower cords spaced by web members in a zig-zag arrangement. More particularly the invention relates to means of connecting the web members to one another and to the cords. A wood truss as above is also called a lattice girder.

BACKGROUND OF THE INVENTION AND PRIOR ART

British Pat. No. 733,288 issued to Gerlach and published in 1955 teaches a wooden lattice girder in which the lattice members are finger scarfed together, with the finger scarfed members extending through the cords. A Swiss Pat. No. 306,573 issued to Kampf in 1955 teaches a lattice girder construction resembling that of Gerlach's in that the lattice members extend through the cords. A Federal German Pat. No. 1,154,253 of 1963 also to Gerlach teaches construction in which, although differing from his British patent above, web members are joined to one another with the joint extending through the cord. U.S. Pat. No. 2,780,842 issued to Hess in 1957 also shows web connected to adjoining web, with the join extending through the cord or, alternatively, through a block secured to the cord.

SUMMARY OF THE INVENTION

In all the known constructions above stress transference is largely web to cord to web. A United States patent application Ser. No. 474,786 now U.S. Pat. No. 3,452,502 issued July 1, 1969 of the present inventor George E. Price assignee, in a Wood Truss Joint was allowed 30 Oct. 1968 but has not yet issued. This teaches a wood truss joint wherein, while there is still some transference of stress from web to cord to web, this is materially less than in the known constructions above. Price has discovered that further reduction of stress transference from web to cord to web is attained by finger scarfing only alternate generally parallel web members to the upper and lower cords, and by finger scarfing oppositely inclined webs only to the inclined webs aforesaid.

All of the joints discussed here are glue bonded according to known procedures. The stresses and stress patterns existing in, and in the vicinity of, joints of this kind are exceedingly complex and are difficult to analyze. While knowledge of these joints is incomplete, there is indication that where webs which are connected to the cords and to other webs are subject to tensile stress, and the intervening webs which are connected only to other webs are subject to compressive stress, advantage results. This advantage is attributed to material reduction of tensile stress perpendicular to the wood grain. Thus a wood truss arrangement according to the present invention can produce a stronger truss than heretofore with webs of the same size.

A detail description following related to drawings gives exemplification of preferred embodiment of the invention which, however, is capable of expression in joints other than those particularly described and illustrated.

DESCRIPTION OF THE DRAWINGS

FIG. 1 is an isometric drawing of a part of an assembled truss constructed according to the invention,

FIG. 2 is a detail section on 2-2 of FIG. 1,

FIG. 3 is a detailed section on 3-3 of FIG. 1,

FIG. 4 is a fragmented isometric drawing showing alternate web to web finger scarfing.

PREFERRED EMBODIMENT**Description of FIG. 1.**

A fragmented truss, generally 10, has an upper chord 11 spaced from a lower chord 12, by an inclined interconnected web member 13 and an oppositely inclined 15 interconnected web member 14. The web member 13 is finger scarfed at a lower end to the lower chord 12 as indicated at 15, an upper end being finger scarfed to the upper chord 11 as indicated at 16.

The oppositely inclined web 14 has a lower end finger scarfed to the inclined web 13 adjacent to, and clear of, the lower chord at 17.

A second inclined web member 19, generally parallel to the web 13, is finger scarfed to the lower and upper chords as shown at 21 and 22.

The oppositely inclined web 14 has an upper end finger scarfed to the web 19 at 23.

A further web member 24 oppositely inclined to the webs 13 and 14 appears fragmented in FIG. 1. A lower end of this web 24 is fingerscarfed at 25 to the inclined web 14 adjacent to, and clear of the lower chord 12.

In FIG. 1 the oppositely inclined webs 24, 14, are shown fingerscarfed to the inclined webs 14, 13, well clear of the lower chord 12. This is for clarity of illustration, in actuality the members 24 and 17 are just clear of the chord.

FINGER SCARFING CONSIDERATIONS AND REFERENCE TO FIGS. 2 AND 3.

As shown in FIGS. 2 and 3, the finger scarfing is substantially triangular in section. For practical reasons the fingers are normally made with flat butts (not shown) at ridges and valleys. Usually the scarfing has a pitch of about 1:6, that is to say that the included angle at the apex of the finger is about 18°. Nevertheless, the invention is of value in the limit where the included angle at the apex is zero, that is to say where the joint becomes a rectangular mortice and tenon.

As described, the webs are connected both to the chord and other webs or to other webs only. It will be apparent that, at ends of the truss, end webs must be connected to the chord only.

The pitch of the finger scarfing has been given as being about 1:6, it has been found that this figure is satisfactory and gives results approaching optimum. It has also been pointed out that large variation in pitch still results in operable joints, practical effective limits of pitch are generally within the approximate limit 1:5 to 1:7.

FIG. 4 ALTERNATIVE

In FIG. 4 a web member 24.1 has finger scarfing to the web 19 differing from the web to web finger scarfing above. The web 24.1 is chamfered as shown at 26 before scarfing so as to provide a flat adjacent to an upper surface 27 of the lower chord 12. This results in lengthening of web members such as 24, 14, with some

increase in section moment, with little weakening of the finger scarfing. This reduces original the length of the finger scarfing from 25 FIG. 1, being the depth of the web member, to about three quarters of that depth, as seen at 26.

I claim:

1. A wood truss including:
  - a. spaced upper and lower cords,
  - b. a plurality of inclined first web members scarfed at each end in facing cord sides, said first web members having substantially the same inclination,
  - c. an oppositely inclined web member between each

pair of adjacent first members scarfed to a side edge of each of said adjacent pair of first members adjacent but spaced from the cords so that load is transmitted to the oppositely inclined web members only through the inclined first web members.

2. A wood truss as claimed in claim 1 in which the finger scarfing of the oppositely inclined web members is chamfered so that said finger scarfing is reduced in length to a length of about three quarters the depth of said oppositely inclined members.
